 The Flex-O-Tube Company, a corporation of
 Delaware

Application December 24, 1941, Serial No. 424,243

3 Claims. (Cl. 121—151)

This invention relates to fluid motors and to a control system for regulating the reciprocation of the movable member of the motor by a reversing valve which is mechanically independent of the movable member but controlled in accordance with the position of said movable member.

It is an object of this invention to improve the art of fluid pressure motors.

Another object of the invention is to control the reversing of the principal movable member of a fluid pressure motor by a floating reversing valve which is controlled in turn by the said principal movable member but is mechanically independent thereof.

A further object of the invention is to control the stopping of the motor by shutting off an exhaust passage to prevent a change of possession of the floating valve and thus to stop the principal movable member at one end of its travel in its cylinder.

Other objects, features and advantages will become apparent from the following description and appended claims.

For the purpose of illustrating the genus of the invention, a typical embodiment thereof is illustrated in the accompanying drawings in Figs. 1 to 6, inclusive, and the operation of the said illustrative embodiment of the invention is diagrammatically illustrated in Figs. 7 to 11 inclusive of the said drawings.

In the drawings:

Fig. 1 is a vertical longitudinal sectional view taken substantially along the line 1—1 of Fig. 3 centrally through a hydraulic cylinder, a reversing valve cylinder and a discharge passage of a hydraulic cylinder body.

Figs. 2, 3, 5 and 6 are transverse vertical sectional views through the hydraulic cylinder body taken substantially along the lines 2—2, 3—3, 5—5 and 6—6 of Fig. 1.

Fig. 4 is a horizontal longitudinal sectional view taken substantially along the line 4—4 of Fig. 2.

Figs. 7 to 11 inclusive are more or less diagrammatic vertical sectional views of a theoretical embodiment of fluid motors embodying the principle of the construction shown in Figs. 1 to 6 inclusive, and depicting especially the relationship of the power piston within its cylinder with respect to its reversing valve in various operative positions of the fluid motor.

Referring to the drawings, and first to Figs. 1, 2 and 3, a cylinder body 14 is provided with a cylinder bore 15 extending longitudinally of the body 14, a reversing valve cylinder bore 16 and a pair of bores 17 and 18 forming discharge and

intake passages, respectively, the latter bores also being disposed axially parallel with the reversing valve bore 16 and the cylinder bore 15. A power piston 20 is disposed in the hydraulic cylinder 15 for reciprocation therein and is provided with a piston shaft 21 which projects through a cylinder end bearing 22, a gasket element 23, and a packing nut 24 threaded to the cylinder body 14 for maintaining the bearing 22 and gasket element 23 tightly assembled to the cylinder body 14 to guide the piston shaft 21 and to prevent leakage by the said piston shaft 21. The reversing valve 25 is disposed in its cylinder bore 16 and comprises four spaced pistons 26, 27, 28 and 29 which are made integral with or rigidly fixed relative to a common shaft 30. The nut 31 is threaded to the cylinder body 14 at the open end of valve bore 16 for closing the latter. An annular valve guide 32 split along the line 33 is disposed in the valve bore 16 about the valve shaft 30 and is tightly maintained in the position indicated in Fig. 1 by means of a set screw plug 34.

Referring also to Fig. 4, it is noted that the open ends of the discharge bore 17 and of the intake bore 18 are threaded for the reception of standard pipe fitting elements 35 and 36 for the discharge or return and supply of pressure fluid from and to the motor. The fitting 36 and associated conduit 39 extend to any suitable source of fluid under pressure. As indicated in Figs. 1, 2 and 4, a pair of bores 37 and 38 extend downwardly from the top of the cylinder body 14 to the end of the hydraulic cylinder 15, these bores making an angle of approximately 60 degrees with respect to the axis of cylinder bore 15. The bores 37 and 38 extend through the intake bore 18 as indicated in Fig. 4, downwardly through the valve bore 16 to the ends of the hydraulic cylinder 15 as shown in Fig. 1. With the reversing valve 25 in the position indicated in Fig. 1, the passage 38 is open through the valve cylinder 16 between the pistons 28 and 29 of valve 25 while piston 26 of the valve 25 closes the bore 37 through the valve cylinder 16, but the lower end of the bore 37 is open between the power cylinder 15 and the valve cylinder 16 permitting discharge of fluid from the power cylinder through the valve cylinder 16.

When the valve 25 is at the other end of its cylinder 16, the left-hand end as viewed in Fig. 1, the piston 29 of valve 25 cuts off the passage 38 through the cylinder 16 but leaves the lower end of the passage 38 open between power cylinder 15 and valve cylinder 16 while the bore 37 is open through the valve cylinder 16 between the pis-

tons 26 and 27 of the reversing valve 25. The second pair of bores 41 and 42 extend downwardly from the top of the cylinder body 14 through the intake bore 18 and reversing valve cylinder 16 to the power cylinder 15 as indicated in Figs. 1 and 4. The bores 41 and 42 extend vertically downwardly through the cylinder body 14 and are disposed a short distance to one side or the other of the center of travel of piston 29 so that the bore 41 will register with an annular groove 43 at the left-hand end of piston 29 when the piston is in the right-hand position shown in Fig. 1, and so that the bore 42 will register with a similar annular groove 44 at the right-hand end of the piston 29 when the latter is at the limit of its travel at the left-hand end of the hydraulic cylinder 15.

As indicated in Fig. 5, the annular groove 43 at the left-hand end of piston 29 not only registers with the intake bore 41 but also registers with a discharge bore 45 which leads from the hydraulic cylinder 15 to the discharge passage 17, but the discharge bore 45 does not communicate with the reversing valve 16. As indicated in Fig. 4, a discharge bore 46, similar to the bore 45 is provided in the same transverse plane with the intake bore 42 so as to register with the annular groove 44 at the right-hand end of piston 29 when the latter is at its left-hand limit of travel within the hydraulic cylinder 15 and the passage 46 communicates between the hydraulic cylinder 15 and the discharge passage 17 without communication with the reversing valve cylinder 16. A needle valve 47 is threaded to the cylinder body 14 in axial alignment with the bore 45 so as to close communication through such bore in order to prevent the reversing movement of the reversing valve 25 and thereby stop operation of the piston 29 when the valve 25 is at the left-hand end of its cylinder 16 and with the piston 29 in the position indicated in Fig. 1.

Referring now to Figs. 1, 2 and 4, bores 50 and 51 are provided in the cylinder body 14 and extend downwardly in a vertical direction from the top thereof and communicate between the discharge passage 17 and the left and right-hand ends of the reversing valve cylinder 16. The piston 29 of the reversing valve 25 is adapted to close the passage 51 when the reversing valve 25 is in the position indicated in Fig. 1, and piston 26 of the reversing valve 25 closes the passage 50 when the reversing valve 25 is at the left-hand end of its cylinder 16. Plugs 52 threaded to the cylinder body 14 close the upper ends of the bores 37, 38, 41, 42, 46, 50 and 51. A small diametered weep bore 53 leads from piston shaft 21 through the bearing 22 to an annular groove 54 in the periphery of the bearing 22, and this annular groove registers with a slightly inclined bore 55 which leads to the discharge bore 51.

Figs. 7 to 11 inclusive diagrammatically depict a theoretical embodiment in which the various parts are given numerals 100 higher than the corresponding parts in the practical embodiment shown in Figs. 1 to 6 inclusive. The operation of the embodiment shown in Figs. 1 to 6 will be explained in connection with the diagrammatic illustration depicted in Figs. 7 to 11 inclusive.

In Figs. 7 to 11 inclusive, the intake passages 137, 138, 141 and 142 have associated therewith the arrows "I" indicating intake passages while the discharge passages 146, 147, 151 and 150 have associated therewith the arrows "D" indicating discharge passages. Figs. 1 and 7 illustrate the power piston 120 at the right-hand end of the

power cylinder 115 with the angular groove 143 in the power piston brought into registry with the intake passage 141 and with the discharge passage 145. The needle valve 147 is assumed to be open at this time. The split bearing 132 for the reversing valve 125 not only serves as a bearing but also as a stationary partition interposed between the pistons 127 and 128 shown in Fig. 7. The provision of the annular groove at the left-hand end of the power piston allows relief of pressure within the chambers lying between the piston 127 and the split bearing 132 while the intake passage 142 is cut off by the power piston so that at this time no pressure relief is afforded within the chamber lying between the split bearing 132 and the piston 128. This causes the reversing valve 125 to be moved to the right-hand position indicated in Fig. 7 since any pressure in the chamber lying between the piston 126 and 127 would impress equal forces on opposed end faces of such pistons and would thus counterbalance each other while the same conditions would exist in any chamber provided between the pistons 128 and 129.

When pressure is relieved in the chamber to the left of the split bearing 132, the chamber immediately to the right of such split bearing would force the reversing valve 125 to the right-hand position shown. With the parts in this position, the intake passage 138 is open to the right-hand end of the power cylinder 115 to move the power piston 120 to the left, the piston 129 of the reversing valve 125 cutting off the passage 151 to prevent discharge from the right-hand end of the power cylinder. The piston 126 of the reversing valve at this time cuts off the upper end of the intake passage 137 and the reversing valve cylinder, but the lower end of the passage 137 is open between the left-hand end of the power cylinder, and the left-hand end of the reversing valve cylinder permitting discharge from the power cylinder 115 to the discharge passage 150 to relieve pressure to the left of the power cylinder 120 during the left-hand stroke of the power piston.

As indicated in Fig. 8 the reversing valve 125 remains at rest during the left-hand stroke of the power piston since both intake passages 141 and 142 are cut off by the piston 120 so that pressure within the chambers to the right or left of the split bearing 132 equalize each other while pressures within the chambers between the pistons 126 and 127 or between the pistons 128 and 129 exert equal forces on opposed piston end faces so that there is no tendency to dislodge the reversing valve 125 from the position indicated in Fig. 7 or 8.

When the power piston 120 arrives at the left-hand end of the hydraulic cylinder as indicated in Fig. 9, the annular groove 144 at the right-hand end of piston 120 registers with the intake passage 142 at discharge passage 146 relieving pressure within the chamber between the split bearing 132 and piston 128 while the intake passage 141 is cut off by the power piston 120 so that the chamber immediately to the left of the split bearing 132 maintains its pressure to force the reversing valve 125 to the left-hand end of its cylinder 116 to the position indicated in Fig. 10.

With the reversing valve 125 in the position shown in Fig. 10, the intake passage 137 admits pressure fluid to the left of the power piston 129 since the piston 126 no longer cuts off the intake passage 137 but rather does cut off the discharge passage 150 to prevent relief of pressure

at the left-hand end of the power cylinder, while at the same time the piston 129 of reversing valve 125 cuts off the intake passage 133 at cylinder 116 but permits passage through the lower end of the bore 138 and communication between the right-hand end of the power cylinder and the discharge passage 151 to the right-hand end of the reversing valve cylinder 116 relieving pressure to the right of the power piston 120. This causes right-hand movement of the piston 120 as indicated in Fig. 11. As the power piston 120 moves from the position indicated in Fig. 10 to the position shown in Fig. 11, so the power cylinder 120 cuts off both intake passages 141 and 142 thus equalizing pressure within the chambers to the right and left of the split bearing 132 while pressure within the chambers lying between pistons 126 and 127 and between pistons 128 and 129 apply to equal areas and opposed faces of such pistons and thus counterbalance each other. This permits the valve 125 to remain in the position shown in Fig. 11 until the annular groove 143 again registers with the intake passage 141 to cause a reversal of the valve 125 to the position indicated in Fig. 7.

If at any time the needle valve 147 of the embodiment shown in Figs. 7 to 11 is screwed down to its seat closing the discharge passage 145, operation of the motor can continue only until the reversing valve 125 reaches the left-hand position as indicated in Fig. 11 and the power piston 120 moves to the right-hand end of the power cylinder 115, the position of the power pistons in Figs. 1 and 7, at which time the annular groove 143 of Fig. 11 could no longer relieve the pressure in the chamber immediately to the left of the split bearing 132 so that the reversing valve 125 could not be moved to the right and operation of the motor would stop. Speed control may be obtained by throttling the intake flow.

As many changes may be made in the above indicated construction, and many apparently widely different embodiments of this invention could be had without departing from the spirit and scope thereof, it is intended that all matter contained in the above description or shown in the accompanying drawings shall be interpreted as illustrative and not in a limiting sense.

What is claimed is:

1. In combination with a hydraulic cylinder, a power piston therein, means for introducing fluid under pressure selectively upon either side of said power piston, said means comprising a source of pressure fluid and members defining passages from said source of pressure fluid to points within said cylinder on either side of said power piston, valve means comprising a cylinder and a pair of spaced pistons for alternately opening one and closing another of said passages, a pair of passages leading from said source to said valve cylinder and to the cylinder for said power piston independently of the first mentioned passages, said valve means including a second pair of spaced pistons, and a stationary partition disposed in said valve cylinder intermediate said last-named pistons on said valve for separating said pair of passages one from another, said pair of passages being so arranged that said power

piston at each limit of its travel opens one of such passages while keeping the other passage closed to cause pressure fluid impressed on the valve and on said partition by said first passage to operate the valve and reverse the direction of travel of the power piston.

2. In combination with a hydraulic cylinder, a power piston therein, means for introducing fluid under pressure selectively upon either side of said piston, said means comprising a source of pressure fluid and members defining passages from said source of pressure fluid to points within said cylinder on either side of said power piston, valve means comprising a shaft and a pair of spaced pistons one fixed to each end of said valve shaft, a second pair of pistons fixed in spaced relation on said valve shaft intermediate said first-named pistons, said first-named pair of pistons being arranged for alternately opening

one and closing another of said passages, a valve cylinder for said valve means, a split bearing arranged within said valve cylinder about said valve shaft and fixed to the cylinder intermediate the second-named pair of pistons fixed to the

25 valve shaft, and a pair of passages leading from said source to the valve cylinder and to said power piston, said split bearing separating passages of said pair within the valve cylinder, said pair of passages being so arranged that said power piston at each limit of its travel opens one of said pair of passages while keeping the other closed to cause pressure fluid impressed on the valve and on said split bearing from said closed passage to operate the valve and reverse the direction of travel of the power piston.

3. In combination with a hydraulic cylinder, a power piston therein, means for introducing fluid under pressure selectively upon either side of said piston, said means comprising a source

40 of pressure fluid and members defining passages from said source of pressure fluid to points within said cylinder on either side of said power piston, valve means comprising a shaft and a pair of spaced pistons one fixed to each end of said

45 valve shaft, a second pair of pistons fixed in spaced relation on said valve shaft intermediate said first-named pistons, said first-named pair of pistons being arranged for alternately opening one and closing another of said passages, a valve cylinder for said valve means, a split bearing arranged within said valve cylinder about said valve shaft and fixed to the cylinder intermediate the second-named pair of pistons fixed to the

50 valve shaft, a pair of passages leading from said source to the valve cylinder and to said power piston, said split bearing separating passages of said pair within the valve cylinder, said pair of passages being so arranged that said power piston at each limit of its travel opens one of said pair of passages while keeping the other closed to cause pressure fluid impressed on the valve and on said split bearing from said closed passage to operate the valve and reverse the direction of travel of the power piston, and other means for closing one passage of said pair of passages to stop operation of said piston.

NORMAN M. COUTY.
